UNITED STATES PATENT OFFICE.

EDWARD L. NELSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

MODULATING AND TRANSMITTING SYSTEM.

1,349,729.

Specification of Letters Patent.

Patented Aug. 17, 1920.

Application filed March 8, 1918. Serial No. 221,341.

To all whom it may concern:

Be it known that I, EDWARD L. NELSON, a citizen of the United States, residing at East Orange, in the county of Essex and State of New Jersey, have invented certain new and useful Improvements in Modulating and Transmitting Systems, of which the following is a full, clear, concise, and exact description.

10 This invention relates to oscillating and transmitting systems.

An object of the invention is to improve modulating and transmitting systems for signaling, and particularly for signaling by 15 wireless methods.

A particular object of the invention is to improve upon transmitting means of the kind stated in which a high frequency oscillation generator works directly into an 20 antenna or transmitting conductor and wherein the currents generated by the high frequency generator are directly modulated by an associated low frequency generator.

A more general object is to couple together oscillating audions or similar electric discharge devices in a new and useful manner.

An embodiment of the invention is illustrated diagrammatically in the accompanying drawing and consists in the combination of low frequency and high frequency vacuum tube oscillators of the audion or three-electrode type connected by such circuits that the high frequency oscillations are modulated in accordance with the low frequency oscillations. The frequency of the latter may be instantaneously changed by a key, thereby causing signals to be transmitted.

The tube O, which is of the audion or 40 three-electrode type, functions as a high frequency oscillator and has an oscillation circuit consisting of aerial 1, coil 2, capacity 3 and conductor 4 to ground. The feed-back potential is applied to the control electrode 45 or grid by means of capacity 3 which is variable, through capacity 5 which is connected to the lower end of antenna coil 2. Leak resistance 6 connects the grid and filament in the usual manner and the plate or 50 anode is variably connected to coil 2 through condenser 7.

Tube O' functions as a modulating oscillator and has an oscillating circuit including 55 variable capacity 8, inductance 9, including a portion 10 and condenser 11. Stopping

condenser 13 assists in maintaining a proper potential upon the grid of tube O' and high resistance 12 serves as a grid leak. Portion 10 of inductance 9 is shunted when key K is closed. The filament or cathode is connected to the junction point of inductance 10 and capacity 11 by conductor 14. Conductor 15 connects the anode to the common terminals of capacity 8 and one end of coil 9. The source of electromotive force 16 serves to supply plate-filament current to both tubes through choke coil 17 which serves to keep constant the sum of the plate-filament currents. The inductance 18 acts as a high frequency choke and serves to prevent the 60 high frequency oscillator from reacting upon the low frequency oscillator. Since coil 17 will always have considerable capacity reactance at high frequencies, coil 18 will also serve to annul the capacity effects of 70 coil 17 in the circuit consisting of elements 1, 2, 7, 18, 17, 16, 4 to ground, through which circuit it is desirable that no high frequency current shall pass. Source of electromotive force 19 serves to heat the filaments of the 80 oscillators.

Operation: Since the impedance between the anode and the cathode of the tube O' will vary substantially sinusoidally at the frequency at which the adjustment of circuit 8, 9, 10 and 11 is, at any instant, causing it to oscillate, this will cause corresponding changes of voltage to be impressed across the anode and the cathode of tube O. Thus while the tube O is continually oscillating at 90 a relatively high frequency compared to the frequency of the variations of impedance of the tube O', the oscillations as set up by the tube O will continually vary in amplitude in accordance with the oscillations of 95 O', on account of the variation in the anode-cathode voltage impressed on the tube O. From another aspect the coil 17 and source 16 may be regarded as a source of constant current which cannot undergo material 100 changes during the period of one cycle of oscillator O'. Then as O' cyclically varies in impedance the space current therethrough varies correspondingly. When the tube O' takes more space current the tube O must 105 necessarily take less and vice versa. The amplitude of the oscillations of tube O will be an almost linear function of the instantaneous value of the space current therethrough. The variations of current through 110

system O' may be of any magnitude which will cause suitable variations through system O. Both tubes are set oscillating and in order to transmit signals the frequency 5 of oscillations generated by tube O' is changed by closing key K. The signals thus produced are received at a receiving station in a manner well understood by those skilled in the art.

10 The invention is not limited to the circuit arrangement shown and described, which is merely illustrative. The various features of the invention, all of which are of more or less general application, are set forth in the 15 appended claims.

What is claimed is:

1. In a transmitting system, an oscillation circuit including an antenna, a three-electrode vacuum tube associated with said circuit 20 to generate oscillations therein, a second three-electrode vacuum tube associated with said first mentioned tube, an oscillation circuit for said second mentioned tube, a source of anode-cathode current for said 25 tubes, a circuit through which the current is supplied, and means in said circuit for maintaining the sum of the currents through said tubes constant.

2. In a radio system, an oscillation circuit including an antenna, a means for generating oscillations therein including a three-electrode vacuum tube, a second oscillation circuit, a second means for generating oscillations therein including a second 35 three-electrode vacuum tube, a source of anode-cathode current for the tubes of said generating means, and a means tending to prevent fluctuation in the total current supplied by said source.

3. In combination, a pair of three-electrode vacuum tubes each producing oscillations in a different circuit, one electrode of each tube being a cathode, a negligible impedance connection between the cathodes 45 and a conductive connection for the anodes having negligible impedance except for a filter element adapted to offer impedance to high frequencies.

4. In combination, a plurality of electrical discharge devices, individual frequency determining circuits for said devices, each said device including a cathode, an anode and a control element, a negligible impedance connection between the cathodes, and 55 a conductive connection for the anodes of negligible impedance except for a filter means adapted to offer high impedance to high frequencies.

5. In combination, a plurality of discharge devices, individual frequency determining circuits for said devices, each said device including a cathode and an anode, a negligible impedance connection between the cathodes, and a conductive connection 65 between the anodes having negligible im-

pedance except for an electrical impedance means adapted to offer impedance to high frequencies.

6. In combination, a pair of three-electrode vacuum tubes, individual frequency determining circuits for said tubes, one electrode of each tube being a cathode, one electrode of each tube being an anode, a negligible impedance connection for the cathodes, and a connection for the anodes which is of negligible impedance except for a coil adapted to offer a high impedance to oscillations of the approximate frequency at which the tube having the highest oscillation frequency is adapted to oscillate.

7. In combination, two oscillation circuits, a pair of three-electrode vacuum tubes each primarily adapted to generate oscillations in one only of said circuits with which it is directly associated, a low impedance connection for one corresponding pair of said electrodes, and a direct connection including a high frequency obstructing element for another corresponding pair of said electrodes, and means tending to keep constant the sum of the anode currents supplied to said tubes.

8. In combination, a vacuum tube, means including feed-back circuits therefor whereby the tube acts as a generator of oscillations, a second vacuum tube, other means therefor whereby the second tube acts as a generator of oscillations, means whereby the oscillations generated by the first of said tubes are modulated according to the oscillations generated by the second, and means for maintaining the sum of the anode currents through said tubes constant.

9. In combination, a three-electrode vacuum tube oscillating generating system, a second three-electrode vacuum tube oscillation generating system, two elements of each tube being an anode and a cathode, means whereby the oscillations of one system may be modulated according to the oscillations 100 of the second, means for supplying anode-cathode current, and means for keeping the sum of the anode-cathode currents of said systems constant.

10. In combination, an oscillation generating system including a discharge device, a second oscillation generating system including a discharge device, feed-back connections for said systems, means for producing a space current in each system, 110 means whereby the oscillations of one system may be modulated according to the oscillations of the second, and means for keeping the sum of the space currents of said systems constant.

11. In combination, a plurality of oscillation generating systems, each said system including an electrical discharge device having an impedance controlling element, an anode and a cathode, means for producing an 120

130

anode-cathode current in each system, and means for keeping the sum of the anode-cathode currents of said systems constant.

12. In combination, a plurality of connected oscillation generating systems, each having a discharge device including an anode, a cathode and a control element, and means for keeping the sum of the anode-cathode currents of said systems constant.

13. In combination, a plurality of con-

nected oscillation generating systems, each having a discharge device including an anode and a cathode, a feed-back for each discharge device and means for keeping the sum of the anode-cathode currents of said systems constant.

In witness whereof I hereunto subscribe my name this first day of November, A. D. 1918.

EDWARD L. NELSON.
